UNITED STATES PATENT OFFICE

HENRY C. DENSLAW, OF BROOKLYN, NEW YORK

MOVING CURTAIN MACHINE FOR EDUCATIONAL AND ADVERTISING PURPOSES

Application filed May 28, 1930. Serial No. 455,095.

My invention relates to moving-curtain machines in which rollers operate in conjunction with a moving and pausing display curtain bearing a lengthy showing of pictures, consecutive lessons, expanding developments or progressive story events to be read and viewed by many and often at a distance.

Exhibitors have been known of rolling 19 ribbons, strips or bands but not adapted mechanically for very wide and very long moving curtains and the objects of my invention are, first, by means of double cooperating curtains to make possible ready exchange- 15 ability of the outer display curtain; second, to provide roller mechanism on which very long wide curtains will not creep sidewise and bind; third, to make practical great length and also width of display in an up- 20 right shallow case; fourth, to have regulatable timed pauses as needed for the better reading or view of the displays; fifth, a provision for checking the curtain at any point 25 for talks upon the portion in view; sixth, provision for self-stopping at the end where the beginning title appears again at the top should no one be interested in continuing it or viewing it further; seventh, to have regulable curtain speed.

30 A practical need was felt for this machine and as nothing for the purpose could be found in use or on the market I took up inventing and constructing and gave thorough and successful trial to this machine in actual 35 use with results that indicate a practical and attractive new device for the classroom, foyer, hallway, museum, show window, bulletin board, etc. All the related past devices showed that different mechanics providing 40 lower roller flexibility of movement was needed in order to have this entirely new large size of curtain display.

Wide curtains function when narrow curtains cannot because of a lack of visibility 45 and readability at a distance, but wide curtains are inclined to creep sidewise and bind. This difficulty is overcome on the following principles: wide curtains should hold up lower rollers as though they were simply 50 hanging in downward curtain loops, so free

to turn over, to rise and to fall, and so light in weight that wide curtains, due to side pressure of lower roller flanges can easily shift beneath lower rollers whenever necessary and thus curtains can keep aligned with 55 top rollers. My result of practical readability is obtained, not simply through difference in size of curtains, but through new structure as described below in detail making 60 large size possible.

By having the element of weight to keep certain taut situated only within every lower roller, and by having practically no friction upon axles of said rollers from attached weight or springs, I obtain maximum ease 65 of rolling. By confining essential fixed spacing of said rollers only to very light hanging axle-bars so loosely retained in axle-bar-holders that said axle-bars in one-way-movement pull of curtain operations, touch said holders only at top front portion of axle-bar, I gain most flexible rising and falling movement of 70 lower rollers, essential because of unevenness of curtains or of protruding exhibits on surface of outer curtains; I also gain said flexibility of movement most free in rear rollers where most needed and least free at front rollers, giving most tautness of curtain across 75 show face where most needed taut. By having suspended in lower loops of curtains 80 aligned, easy turning, polished rollers, sufficiently light so curtains can when necessary shift below any lower rollers thus realigning curtain again with flannel-faced upper rollers and big rough-surfaced driving rollers. 85 My test shows a shifting from side pressure of lower roller flanges against curtain sufficient to safeguard wide curtains from creeping sidewise on lower rollers and doubling or fraying at edges or eventually 90 binding.

I also found that double endless curtains were necessary in order to obtain a ready exchange of display curtains. By means of 95 double cooperating endless curtains, each different in material, structure and function from the other curtain but combining for one end; first, an inner curtain with both ends fastened together and sealed, serving as guide-curtain whenever a change of outer cur- 100

tain is put on, and as alignment-curtain because of stiff texture, serving both functions by means of structurally incorporated permanent fasteners or clasps to guide and 5 retain the outer curtain in line; second, a prepared-for-show outer curtain which when put on the machine in place of another is first guided over, under and between the rollers by the inner curtain and like said inner 10 curtain is fastened together and sealed at the ends, thus giving the outer curtain the necessary and greater tensile strength and more even lay of surface, both due to being made endless; also the outer curtain is of 15 different material from the inner curtain and suitable for drawing, lettering, painting, and otherwise decorating for display.

Figure 1 is a view of a moving curtain machine showing a preferred form of embodiment of my invention with certain parts shown in section, others in elevation and with portions of various parts indicated as broken away to better show arrangement of structure.

25 Figure 2 is a vertical sectional view substantially on line 2—2 of Fig. 1.

Figure 3 is a detail view partly in section on line 3—3 of Fig. 1.

Figure 4 is an enlarged detail view of an 30 operating lever and portions of certain of the parts with which it is shown associated in Fig. 1.

Figure 5 is a detail view in perspective of a stopping button arranged to project from 35 the face of the curtain.

Figure 6 is a detail sectional view of superposed curtain fabrics on line 6—6 of Fig. 1 and shows a form of clasper for holding the two curtains in register.

40 Figure 7 is a sectional view on line 7—7 of Fig. 1.

Figure 8 is a sectional view on line 8—8 of Fig. 1.

45 Figure 9 is a sectional view on line 9—9 of Fig. 2.

Figure 10 is a diagrammatic view of an electric circuit for controlling operation of the machine.

Referring to the drawings, a moving curtain and mechanism for actuating it are enclosed within the casing 1 which is provided with a glass front 2. Secured to the inner side walls of the case are blocks or cleats 3 in which are formed bearings for the axles 50 of rollers, as the large main roller 4, intermediate guide rollers 5 and 6, and lower guide rollers 7, 8 and 9. The large main roller 4 supports a major portion of the multiply curtain 10 and frictionally engages it 55 in driving relation. About the guide rollers 5 and 6 the curtain passes in upward loops 11 and 12 thereby forming the downward loops 13, 14 and 15, within which are suspended tensioning rollers 16, 17 and 18. The 60 guide rollers 7, 8 and 9 serve to separate cer-

tain adjacent runs of the curtain and prevent interference therebetween. In order that they may freely perform their function of tensioning the curtain the axles of the tensioning rollers are freely journaled in 70 aligning floating axle bars 19 and the latter are also permitted considerable freedom of bodily movement by retaining guides 20. As shown, all except the guide rollers 7, 8 and 9 are provided with curtain retaining end 75 flanges.

The structure of curtain 10 includes the outer ply 21 and inner ply 22. Each of these plies is joined to itself to form an endless band with a transverse seam which comprises 80 a strip 23, as of flexible steel, folded into its respective end of material, stitches 24 securing each fold with its strip included, tie members 25 surrounding adjoining folds and enclosed strips, and sealing tapes 26 85 cemented over the joints thus formed. At a suitable number of places, the superposed plies of the curtain are secured together by the staples of clasps 27.

Means for driving the main roller 4 include the motor 28, reduction gearing indicated by 29, a belt pulley 30 and a belt 31 which passes around the pulley and also around a grooved end flange of said roller. As shown, the roller driving means may be 90 housed in a separate compartment at the top of the casing. In a similar adjacent compartment there is shown a motor and associated mechanism for establishing driving and non-driving periods for the roller- 100 driving motor 28. This second motor 32, through reduction gearing indicated by 33, drives an interrupter for controlling the roller driving motor 28. Said interrupter 34 by which is determined the duration of 105 alternate periods of curtain rest and movement, includes the worm 35, which engages and drives the worm wheel 36. Associated with the worm wheel are a series of non-conductor segments 37, as of mica, and conductor segments 38. Segments of either or both materials being adjustably secured to the worm wheel so that alternate areas of conductor and non-conductor surface of different extent are available. Adapted to 110 contact with these areas under slight spring pressure is a conductor drag 39 which interrupts current in the motor circuit.

Two switches 40 and 41 are provided (see Figs. 1 and 10) for control of the electric 115 current including the motors 28 and 32, the interrupter 34, and the rheostats 42 and 43 respectively for said motors 28 and 32. The switch 40 has associated therewith an operating rod 44 which is provided with a spring 120 45 attached to an eyebolt 46. A ferrule, notched as at 47, is secured to rod 44 to receive a detent 48 at one end of a rod 49, which at its other end is pivoted to a lever 50 fulcrumed in brackets 51 at the top of the cas- 125 130

ing. The ferrule and detent are suitably guided by a fixture 52 secured to the casing. For the purpose of urging the detent toward the ferrule and for also moving a free arm 53 of lever 50, into the path of a stopping button 54 which is secured to the curtain, a spring 55 is attached to the lever and anchored to the casing. As a guide for the free arm 53 of lever 50 a slotted member 56 is 5 attached to the casing. From its open position, switch 40 may, through rod 44, be moved by a hand lever 57 to its closed position, which after the switch is locked in closed position by detent 48 becomes thereafter ineffective until open position of the switch is again established by withdrawal of the detent, as when the stopping button 54 comes into contact with the arm 53. In other words, as soon as the detent is withdrawn 10 from notch 47 spring 45 actuates rod 44 thereby opening the switch, stopping the motor and again placing the rod in position where it may be actuated by hand lever 57. Switch 41 is operable at any time by means 15 of a hand lever 58 which is connected to the switch by a rod 59.

Having thus described my invention, what I claim is,

1. An exhibitor including in combination, 30 a casing, a flanged roller journaled within the casing, an inner curtain supported upon and adapted to be driven by the roller, a display curtain overlying and removably secured to the inner curtain, a series of rollers 35 comparatively remote from the driving roller and about which the associated curtains are adapted to pass in downward loops, roller means journaled within the casing, interposed between the driving roller and the remote rollers and about which the associated curtains are adapted to pass in upward loops, oppositely disposed axle bars within which the remote rollers are journaled to thereby form bodily movable frames, and retaining 40 boxes secured to the casing and adapted to receive respective ends of axle bars in an arrangement adapted to permit bodily movement thereof within certain limits.

2. An exhibitor including in combination, 50 a casing, a flanged roller journaled within the casing, a curtain supported upon and adapted to be driven by the roller, a series of rollers comparatively remote from the driving roller and about which the curtain is adapted to pass in downward loops, roller means journaled within the casing, interposed between the driving roller and the remote rollers and about which the curtain is adapted to pass in upward loops, oppositely disposed axle bars 55 within which the remote rollers are journaled to thereby form bodily movable roller frames, and retaining boxes secured to the casing and adapted to receive respective ends of axle bars in an arrangement adapted to permit bodily 60 movement thereof within certain limits.

3. An exhibitor including in combination, a casing, a flanged roller journaled within the casing, a curtain supported upon and adapted to be driven by the roller, a series of rollers comparatively remote from the driving roller, entirely free for universal bodily movement relative to the casing and about which the curtain is adapted to pass in downward loops, roller means journaled within the casing, interposed between the driving roller and the remote rollers and about which the curtain is adapted to pass in upward loops, and means for maintaining the axes of the remote rollers in fixed relation to each other. 70

4. An exhibitor including in combination, a casing, a flanged roller journaled within the casing, a curtain supported upon and adapted to be driven by the roller, a series of rollers comparatively remote from the driving roller and about which the curtain is 80 adapted to pass in downward loops, roller means journaled within the casing, interposed between the driving roller and the remote rollers and about which the curtain is adapted to pass in upward loops, means for maintaining the axes of remote rollers in fixed 85 relation to each other, and means for permitting the remote rollers to move bodily at either end as a group.

5. In an exhibitor, in combination, a casing, a flanged roller journaled in the casing, an endless curtain supported and driven by the roller, anti-friction means for supporting depending runs of the curtain, anti-friction weighting means suspended entirely by the curtain within the downward loops thereof, and guide rollers journaled in the casing adjacent the anti-friction weighting means. 95

6. A strip of material with end edges thereof united by a joint to form an endless curtain said joint comprising substantially abutted folded end edges of the material, a reinforcing strip associated with each of said folded edges, tie loops including therein both abutted edges and both strips, and a protecting tape secured over the tie loops and the joint included by said tie loops. 105

7. A pair of endless curtains of substantially equal length, with one of said pair overlying the other and metal staples incorporated within the surfaces of the inner curtain, the points of said staples extending outwards through the outer curtain and being clinched over the surface of said curtain. 115

8. A pair of endless curtains of substantially equal length with one of said pair overlying the other, each of the curtains comprising a strip of material with the end edges thereof united by a separable transverse joint, and metal staples incorporated within the surfaces of the inner curtain, the points of said staples extending through the outer curtain and being clinched over the surface of said outer curtain. 120

9. An exhibitor including in combination, 125

an endless display curtain, a roller for supporting and driving the curtain, an electric motor for driving the roller, a switch for controlling the motor, a rod associated with the switch, automatic means for actuating the rod to open the switch, means for moving the rod to a position to close the switch, a spring actuated detent for holding the rod in switch closing position, and means associated with the curtain for withdrawing the detent and thereby permitting the switch to be opened by the automatic means.

10. An exhibitor including in combination, an endless display curtain, a roller for supporting and driving the curtain, a motor for driving the roller, a rotatable circuit interrupter for starting and stopping the motor, a second motor for rotating the interrupter, a switch for controlling the second motor, a lever for actuating the switch, and an elongated link interposed between said lever and the switch.

11. An exhibitor including in combination, an endless display curtain, a roller for supporting and driving the curtain, a motor for driving the roller, a rotatable circuit interrupter for starting and stopping the motor, a second motor for rotating the interrupter, a switch for controlling the second motor, a rod associated with the switch, automatic means for actuating the rod to open the switch, means for moving the rod to a position to close the switch, a spring actuated detent for holding the rod in switch closing position, and means associated with the curtain for withdrawing the detent and thereby permitting the switch to be opened by the automatic means.

12. An exhibitor including in combination, an endless display curtain, rollers for supporting the curtain in upward loops of spaced runs, rollers for tensioning the curtain freely suspended in downward loops, a motor for driving one of the curtain supporting rollers, an interrupter for controlling an electric circuit including said motor, a second motor for driving the interrupter also included in said circuit, and a switch for controlling said circuit.

13. In an exhibitor, in combination, a casing, a flanged roller journaled in the casing, an inner curtain supported upon and adapted to be driven by the roller, a display curtain overlying and removably secured to the inner curtain, means for separably joining ends of the display curtain, similar means for joining ends of the inner curtain, anti-friction means for supporting depending runs of the superposed curtains, anti-friction means suspended entirely by the curtains within the downward loops thereof to tension the same, an electric motor for driving one of the curtain supporting rollers, a switch for controlling the motor, a rod associated with the switch, automatic means for actuating

the rod to open the switch, means for moving the rod to a position to close the switch, a spring actuated detent for holding the rod in switch closing position, and means associated with one of the curtains for withdrawing the detent and thereby permitting the switch to be opened by the automatic means.

14. In an exhibitor, in combination, a casing, an endless curtain mounted therein in spaced runs including downward loops, rollers suspended entirely by the curtain within the downward loops, and oppositely disposed bars with which respective ends of the rollers are pivotally associated in a manner to permit either bar to move bodily with the rollers or to partake of a rotative movement about the axis of any one of said rollers.

15. In an exhibitor, in combination, a casing, a curtain mounted therein and disposed in spaced runs terminating in upward and downward loops, rollers suspended entirely by the curtain within the downward loops, and oppositely disposed bars with which respective ends of the rollers are pivotally associated in a manner to permit either bar to move bodily with the rollers or to partake of rotative movement about the axis of any one of said rollers.

16. An exhibitor including in combination, an endless display curtain, a roller for supporting and driving the curtain, a motor for driving the roller, a circuit interrupter for starting and stopping the motor, said interrupter comprising rotatable elements and a stationary element, means for driving the rotatable elements, and means for permitting adjustment of the rotatable elements with reference to their respective durations of contact with the stationary element.
